(57) **CLAIM**

The ornamental design for a mid-clamp for roof mounted photovoltaic modules, as shown and described.

DESCRIPTION

FIG. 1 is a top perspective view of a mid-clamp for roof mounted photovoltaic modules according to the design; FIG. 2 is a bottom perspective view thereof; FIG. 3 is a top plan view thereof; FIG. 4 is a front elevational view thereof, the rear elevational view being identical; and, FIG. 5 is a side elevational view thereof, the other side elevational view being identical.
